[57] **CLAIM**

The ornamental design for a combined multiple com-

partment trash container and base therefor, as shown and described.

DESCRIPTION

FIG. 1 is an exploded perspective view of a combined multiple compartment trash container and base therefor showing my new design, the base is omitted for clarity of illustration;

FIG. 2 is a side elevational view of FIG. 1, the opposite side elevational view being a mirror image of that shown;

FIG. 3 is a top plan view of FIG. 1;

FIG. 4 is a bottom plan view of the multiple compartment trash container;

FIG. 5 is a top perspective view of an insert of the multiple compartment trash container;

FIG. 6 is a side elevational view of FIG. 5, the opposite side elevational view being a mirror image of that shown;

FIG. 7 is a top plan view of FIG. 5, the bottom is flat and unornamented;

FIG. 8 is a top perspective view of the base, the multiple compartment trash container is omitted for clarity of illustration;

FIG. 9 is a side elevational view of FIG. 8;

FIG. 10 is a top plan view of FIG. 8, the bottom is flat and unornamented; and,

FIG. 11 is a top perspective view thereof.

FIG.1.

FIG. 5.

FIG. 6.
